UNITED STATES PATENT OFFICE.

JOHN J. MOONEY, OF NEW ORLEANS, LOUISIANA.

DESIGN FOR A VENTILATOR-CAP.

SPECIFICATION forming part of Design No. 15,416, dated September 16, 1884.

Application filed May 13, 1884. Term of patent 11 years.

To all whom it may concern:

Be it known that I, JOHN J. MOONEY, a citizen of the United States, residing at New Orleans, in the parish of Orleans and State of Louisiana, have invented and produced a new and original Design for Ventilator-Caps, of which the following is a specification.

My design consists, essentially, of a cylindrical base portion and a cap proper, conical in form, and provided with a plurality of gable-like or dormer projections, disposed at even distances around the cone, said projections being situated at such a point between the base and apex of the cone as to produce a harmonious effect. I prefer to make the cone rather sharply pointed, as I find such shape to give the most pleasing appearance; but in producing the design the angle of the cone may be varied without departing from my design. I also prefer to ornament the cone and gable-like projections as will be described.

To illustrate my design I have embodied it in a ventilator-cap, of which the accompanying drawing is a representation.

Figure 1 is an elevation of the ventilator-cap. Fig. 2 is a top plan view of the same.

A represents the base portion, and B the conical portion, of the cap, the latter being pro-

vided with the dormer projections C. The cap is ornamented around its lower edge by a downwardly-projecting fringe of points, b, and at its apex by a slender spire, b', upon which is transfix a ball, b''. The projections C are also shown as having an upwardly-projecting fringe of points, c.

I have shown the fringe hereinbefore referred to as consisting of a series of acute points having a series, equal in number, of circular apertures arranged between their bases.

What I claim is—

1. In a design for a ventilator-cap, the cylindrical base A, having the downwardly-extending fringe b, the conical portion B, and the dormer projections C, as set forth.

2. In a design for a ventilator-cap, the cylindrical base A, the conical portion B, and the dormer projections C, having the upwardly-extending fringe c, as set forth.

In testimony whereof I have hereunto set my hand, this 5th day of May, 1884, in presence of two witnesses.

JNO. J. MOONEY.
